UNITED STATES PATENT OFFICE.

RAFF FRANK CAGE, OF ASBURY PARK, NEW JERSEY.

MATCH-SAFE.

SPECIFICATION forming part of Letters Patent No. 687,119, dated November 19, 1901.

Application filed May 20, 1901. Serial No. 61,087. (No model.)

To all whom it may concern:

Be it known that I, RAFF FRANK CAGE, a citizen of the United States, residing at Asbury Park, in the county of Monmouth and 5 State of New Jersey, have invented certain new and useful Improvements in Match-Safes; and I do hereby declare the following to be a full, clear, and exact description of the invention, such as will enable others skilled 10 in the art to which it appertains to make and use the same.

This invention relates to certain new and useful improvements in match-safes, and has for its object to produce a match-safe which 15 shall be inexpensive to manufacture and contain no parts which can become deranged or inoperative.

A further object is to provide a match-safe from which matches can only be taken one at 20 a time, thus insuring an economical distribution.

A still further object of my invention is to provide a match-safe the sides of which may be indefinite in number, be used for advertising purposes, and permit of the extraction 25 of a match from each side thereof.

With these and other objects in view my invention further consists in the novel details of construction and combination of parts 30 to be clearly described in the following specification and fully set forth in the claims.

Referring to the accompanying drawings, forming a part of this application, and in which like characters of reference indicate 35 similar parts throughout the specification, Figure 1 is a central vertical section of my improved match-safe. Fig. 2 is a horizontal sectional view taken on the line 2 2 of Fig. 1. Fig. 3 is a perspective view of the bottom, 40 showing the connective means partly broken.

In the drawings the reference-numerals 1 indicate the sides of my improved match-safe. These sides may be of any number; but I prefer to use a rectangular case, as 45 shown in the drawings. The sides 1 have integral inwardly-extending flanges 1' at their upper ends for the reception of the removable hood or cap and are mounted on a base or pedestal 2. The sides have also formed there- 50 in an opening 3 of sufficient size to permit of the extraction of a match. I prefer to make

my match-safe pyramidal in shape, which gives an effect pleasing to the eye and makes it of less bulky appearance, requires less material, and, furthermore, admits of the matches 55 being easily placed in their respective guideways when the safe is to be loaded and the cap or hood removed therefrom. Above the opening 3 I provide roughened surfaces for the purpose of igniting the match. 60

On the inside of the sides 1 I secure guideways 4 of sufficient width to allow of the insertion of a match endwise or of such width corresponding to the length of the match and which are formed with pockets 5 at their 65 lower ends, made integral therewith. The guideways 4 are further provided with integral sides 6, which are bent at an angle to the said guideways and form a side wall which prevents the lateral displacement of 70 the match. These guideways extend from the top of the sides 1 to where they terminate in pockets 5 below the top of the opening 3. The space between the guideways and the sides 6 is only sufficient to permit of the passage 75 of one match at a time.

The reference-numeral 7 indicates the removable bottom of my improved match-safe, which is provided with downwardly-extending flanges 8, which make and form a rigid 80 connection with the base. It is furthermore provided with an integral upwardly-extending V-shaped arm 9, having a cross-piece 9' formed integral therewith. Said cross-piece carries an apertured screw-threaded boss 10. 85 A cap or hood 11, also pyramidal in form and having sides which terminate in an apex, has a central opening in its apex and is adapted to be seated on the inwardly-extending flanges of the sides 1. A screw 12 is 90 adapted to have its head engage the sides of the opening and its apex and its threaded portion engage the boss on the arm 9.

The operation of my device is as follows: When it is desired to load the safe, the screw 95 12 is removed, which permits the removal of the hood or cap 11 and the bottom 7. The matches are then placed singly in the guideways 4 until all of the guideways have become filled, when the bottom and cap will be placed 100 on the safe and the same securely locked by the screw 12. It will thus be seen that as

one match is extracted from the pocket 5 another match will immediately take its place by the action of gravity, and thus cause one match to be always presented in the pocket 5 until the safe has become empty. It will be noted that the distance between the guideways is of sufficient width to allow the operator to place the fingers within this space, thereby permitting the match to be easily removed from the pockets.

It will be noted that many changes may be made in the details of construction without departing from the spirit and scope of my invention.

15 Having thus fully described my invention, what I claim as new and useful, and desire to secure by Letters Patent, is—

1. In a match-safe, a series of sides each having an opening, guideways carried on the 20 inner face of each of said sides and terminating at their lower ends in pockets which lie slightly below the top of the openings in the sides, a bottom, a centrally-arranged upwardly-extending arm carried by said bottom, 25 a cap or hood mounted on the upper ends of the sides, and means for securing the cap or hood to said upwardly-extending arm, substantially as described.

2. In a match-safe, the substantially pyramidal sides having inturned upper ends and each provided at the lower end with an opening, guideways carried on the inner faces of the sides and terminating at their lower ends in pockets, a bottom, an upwardly-extending 30 arm carried thereby, a removable cap or hood mounted on the inturned upper ends of the sides, and a screw passing through the apex of said cap or hood and into the upwardly-

extending arm to bind the parts together, substantially as described.

3. In a match-safe, four sides, a base secured to said sides, said sides having an opening formed therein, guideways provided with pockets, said guideways being so formed as to permit of the crosswise insertion of a match 45 therein.

4. In a device of the character described, sides, a base, a removable cap, guideways with integral flanges at right angles thereto mounted in said sides, integral pockets also 50 formed on said sides, in combination with a bottom provided with an upwardly-extending arm, said arm carrying means whereby it may be locked to said removable cap, substantially as set forth.

5. In a device of the character described, the sides, a base on which said sides are mounted, said sides being provided with an opening, guideways with right-angular flanges secured to said sides, said guideways being provided with integral pockets, said sides being provided at their upper ends with integral inwardly-extending flanges, in combination with a removable cap or hood, a bottom provided with an upwardly-extending V-shaped 65 arm, said arm being provided with a threaded boss at its upper end, and a screw whereby said hood and said bottom may be securely locked, substantially as described.

In testimony whereof I affix my signature 70 in presence of two witnesses.

RAFF FRANK CAGE.
